UNITED STATES PATENT OFFICE.

JOHN B. WATLING, OF CHICAGO, ILLINOIS.

SAFETY-BOX.

1,206,959.

Specification of Letters Patent.

Patented Dec. 5, 1916.

Application filed June 15, 1916. Serial No. 103,799.

To all whom it may concern:

Be it known that I, JOHN B. WATLING, a citizen of the United States, and a resident of Chicago, county of Cook, and State 5 of Illinois, have invented certain new and useful Improvements in Safety-Boxes, of which the following is a full, clear, and exact description.

The invention relates to safety boxes and 10 more particularly to cash boxes for coin controlled machines.

Coin controlled machines are frequently exposed in public places and the present invention seeks to provide a cash box for 15 receiving the deposited coins which is of strong construction and which is securely guarded so that access thereto cannot be readily attained except by the person holding the cash box key.

20 The invention consists in the features of construction hereinafter set forth, illustrated in the preferred form in the accompanying drawings and more particularly pointed out in the appended claims.

25 In the drawings, Figure 1 is a view in elevation, partly broken away of the cash box and supporting plate therefor. Fig. 2 is a longitudinal section taken through the machine casing and the cash box. Fig. 3 is a rear elevation of the fastening devices for 30 holding the cash box in position, the latter being shown in section on the line 3 of Fig. 2. Fig. 4 is a detail horizontal section on the line 4 of Fig. 3. Fig. 5 is a detail vertical section on the line 5 of Fig. 3.

In the construction shown the casing 10 of the coin controlled machine is formed of sheet metal and the cash box is secured to the rear face of one of the vertical walls 40 11 of the casing.

The cash box comprises upper and lower end walls 12, a back wall 13 and side walls 14 which are preferably formed of sheet metal. The back and side walls 13 and 45 14 are formed of a single piece of sheet metal and are provided at their upper and lower ends with inturned flanges 15 which overlap the edges of the upper and lower end walls 12 and are secured thereto preferably 50 by spot welding. At their front edges the side walls 14 are provided with inturned flanges 16 of considerable width and the upper and lower end walls 12 are also provided at their front edges with inturned flanges 17 which, at the corners of the box 55 overlap the flanges 16 as most clearly shown

in Fig. 5. The flanges 16 and 17 constitute the front wall of the box and surround a rectangular opening 18 in such front wall. These flanges abut against the rear face of 60 the supporting plate or wall 11 of the machine casing, such wall or plate being provided with a rectangular opening 19 therein which registers with and is preferably of the same size as the opening 18 in the front 65 wall of the box.

Suitable fastening devices which are accessible for releasing the same only from the inner side of the supporting plate 11 and preferably only from the interior of 70 the box, are provided for securing the latter to the supporting plate. In the preferred construction such fastening devices also serve to secure in place a heavy rectangular frame 20, which abuts against the outer 75 face of the supporting plate or wall 11 and surrounds the opening 19 therein. In the preferred construction shown, the rectangular cast-metal frame 20 is provided on its outer face with a raised rib 21 which extends about the opening therein, and on its inner face the frame is provided with a series of integral bosses 22 which extend through holes 23 formed in the supporting plate 11 and in the flanges 16 and 17 as most 80 clearly shown in Figs. 4 and 5, each of the bosses having a tapped hole for receiving a fastening tap-bolt 24. In the construction shown there are six of these fastenings at each of the corners of the cash box and two 85 intermediate its upper and lower ends. In the latter two fastenings, the bosses 22 extend through the supporting plate or wall 11 and through the side flanges 16 and spacing collars 25 surround the inner ends 90 of the bosses. At the corners of the box the bosses 22 extend through the supporting plate or wall 11 and also through both the side and end flanges 16 and 17 as shown in Fig. 5, and short cross straps 26, one at 100 each end of the box have openings therein into which the inner portions of the bosses 22 extend. The spacing collars and straps 25 and 26 abut against the inner faces of the flanges 16 and washers 27 are interposed between the heads of the tap-bolts 24 and the inner faces of the spacing collar and straps. The headed inner ends of the tap-bolts are polygonal in outline so 105 that they may be readily engaged by a suitable wrench. These fastening devices serve to securely hold the cash box and the frame 110

20 in position and the latter serves to strengthen the edges of the openings in the supporting plate and in the box. The inner edges 28 of the frame 20 are 5 slightly beveled and are spaced from the inner edges of the openings 18 and 19 and a heavy cast metal door or cover plate 29 having correspondingly beveled edges fits snugly within the frame with its inner face closely 10 adjacent or abutting against the edge portions of the opening 19 in the supporting plate 11. The door as shown, is provided on its inner face with an integral strengthening rib 30 and at its lower end with an integral, inwardly and downwardly projecting, 15 angle lug 31 which is adapted to overlap the cross strap 26 at the lower edge of the box opening. A lock 32 is secured to the inner face of the door adjacent its upper edge and 20 is provided with a key nose 33 which is arranged within an opening formed in the cover. The bolt 34 of the lock is adapted to overlap the upper flange 17 and project well behind the cast metal frame 20 so that the 25 door can only be removed by first withdrawing the bolt by means of the lock key. The beveled edge door fits snugly within the beveled edge of the frame 20 and the rib portion 21 of the latter projects outwardly beyond 30 the edge of the door so that it is exceedingly difficult if not impossible to insert an instrument between the frame and the edge of the door and pry the latter from position. This guarding and strengthening frame 20 35 and the cash box are secured in place by fastening devices which are not accessible either from the exterior or the interior of the machine casing when the cover plate or door 29 is in position and locked. Hence, only 40 the holder of the key to the lock 32 can have access to the cash box. As in other coin controlled machines, a coin chute 35 leads into the upper end of the cash box.

It is obvious that changes may be made 45 in the details set forth without departure from the essentials of the invention as defined in the claims.

I claim as my invention:—

1. In safety boxes, the combination of a 50 box, a supporting plate therefor, said box and said plate having registering openings, fastening devices accessible only through said openings for securing said box to said plate, and a cover for said openings, substantially as described.

2. In safety boxes the combination of a 55 supporting plate having an opening therein, a box having an opening in its front wall registering with the opening in said plate, fastening devices extending through the 60 front wall of the box about the opening therein for securing said box to said plate, said fastening devices being accessible only through the interior of said box, and a cover 65 for said openings, substantially as described.

3. In safety boxes, the combination of a supporting plate having an opening therein, a box on the inner side of said plate and having an opening in its front wall registering with the opening in said plate, a frame on the outer side of said plate extending about the opening therein, fastening devices accessible only from the inner side of said plate for securing said box and said frame to said plate and a cover fitting within said frame and extending over said opening, substantially as described. 70 75

4. In a safety box, the combination with a supporting plate having an opening therein, a sheet metal box on the inner side of said plate opposite the opening therein, said box being open at its front and having flanges at its front edges abutting against the inner face of said plate, a frame abutting against the outer face of said plate and extending about said opening, fastening devices extending through said flanges and said plate and accessible only from the inner side of the latter for clamping said frame and said flanges to said plate, a cover fitting within said frame and extending over said opening, and a lock for holding said cover in position, substantially as described. 80 85 90

5. In safety boxes, the combination of a supporting plate having an opening therein, a sheet metal box on the inner side of said plate open at its front opposite said opening, said box having flanges at its front edge abutting against the inner face of said plate, a frame abutting against the outer face of said plate and extending about said opening, said frame having integral bosses on its inner face, and said plate and said flanges having holes through which said bosses extend, and tap-bolts and washers co-operating with said bosses for clamping said flanges and said frame to said plate, substantially as described. 95 100 105

6. In safety boxes, the combination of a supporting plate having an opening therein, an open front, sheet metal box on the inner side of said plate opposite said opening, said box having inturned flanges at its front edge abutting against the inner face of said plate, a frame abutting against the outer face of said plate and extending about said opening, fastening devices accessible only through said opening for clamping said flanges and said frame to said plate, and a cover arranged within said frame and extending over said opening, substantially as described. 110 115 120

7. In safety boxes, the combination of a supporting plate having an opening therein, an open front, sheet metal box on the inner side of said plate opposite said opening, said box having inturned flanges at its front edge abutting against the inner face of said plate, a frame abutting against the outer face of said plate and extending about said opening, tap-bolts extending from within 125 130

- said box through said flanges and said plate and into said frame and a cover fitting within said frame and extending over said opening, substantially as described.
5. 8. In safety boxes, the combination of a supporting plate having an opening therein, an open front, sheet metal box comprising end walls and integral rear and side walls, said rear and side walls having flanges over-
10 lapping and secured to said end walls and said side and end walls having inturned flanges at their front edges overlapping one another at the corners of the box, fastening devices extending through the overlapping
15 portions of said inturned flanges for securing said box to the inner face of said plate, and a cover for said opening, substantially as described.
9. In safety boxes, the combination of a supporting plate having an opening therein, an open front, sheet metal box comprising end walls and integral rear and side walls, said rear and side walls having flanges over-
20 lapping and secured to said end walls and said side and end walls having inturned flanges at their front edges overlapping one another
25 at their front edges overlapping one another
- at the corners of the box, and abutting against the inner face of said plate, a frame abutting against the outer face of said plate and extending about said opening, and fastening devices accessible only through said opening for clamping said frame and the overlapping portions of said inturned flanges to said plate, a cover fitting within said frame and extending over said opening, and a lock for securing said cover in position, substantially as described. 30 35
10. In safety boxes, the combination of a supporting plate having an opening therein, an open front box on the inner side of said plate opposite said opening, a frame on the outer face of said plate and extending about said opening, fastening devices accessible only from the inner side of said plate for securing said box and said frame in position, said frame having a beveled inner edge, a cover having a beveled edge fitting within said frame and extending over said opening, and a lock for said cover, substantially as described. 40 45

JOHN B. WATLING.
